(57) **CLAIM**

The ornamental design for a covered wagon door as shown
and described.

DESCRIPTION

FIG. 1 is a rear, right side perspective view of a covered
wagon door showing our new design; and,
FIG. 2 is a rear elevational view thereof.

In the drawings, the dash-dot-dash broken lines depict claim
boundaries and form no part of the claim; the evenly spaced
broken lines illustrate portions of the article that form no part
of the claimed design.
